UNITED STATES PATENT OFFICE.

EUGEN FRIEDLAENDER, OF NEW YORK, N. Y.

MANUFACTURE OF IMITATION FLOWERS FROM FUR.

SPECIFICATION forming part of Letters Patent No. 363,058, dated May 17, 1887.

Application filed March 9, 1887. Serial No. 230,181. (No model.)

To all whom it may concern:

Be it known that I, EUGEN FRIEDLAENDER, of the city, county, and State of New York, have invented certain new and useful Improvements in the Manufacture of Imitation Flowers from Fur, of which the following is a specification.

This invention relates to the manufacture of imitation flowers from fur waste or scraps, to be used as a trimming for ladies' hats, for fancy bouquets, and the like; and the invention consists of an imitation flower made of a suitable stem and core, a spiral layer of fur, and an exterior spirally-wound fastening-wire applied to the fur and stem.

In the accompanying drawings, Figures 1 and 3 represent perspective views of different imitation flowers made from fur according to my invention. Figs. 2 and 4 are vertical transverse sections of Figs. 1 and 3, and Fig. 5 is a rear view of a strip of fur employed for making my imitation fur flowers.

Similar letters of reference indicate corresponding parts.

In the drawings, A represents a core of wood or other suitable material, which forms the center of my improved imitation flower. The core or center A is covered with a suitable textile fabric, such as silk, satin, plush, and the like. The core A is attached to a stem, a, around which is wound a strip, B, of any suitable fur, which is preferably made from waste fur, such as scraps or clippings obtained in the manufacture of fur garments or other articles of fur. This strip B is wound spirally around

the stem below the core in such a manner that the wool and long hair are at the outside of the strip and encircle the core or center A. The strip B is fastened to the stem a by a spirally-wound layer, C, of flexible wire, as shown in Fig. 4, which is covered by any suitable material, and ornamented with tinsel or other suitable fabric. The fastening-wire C holds the layers of fur firmly in position, and produces in this manner a very ornamental flower-like body. The fastening-wire C may also be covered by a hollow mold or shell, D, as shown in Fig. 2. A great variety of ornamental articles can thus be produced, especially as all kinds of fur can be employed, each color and kind of fur giving a different effect, which, when properly matched with cores and fastening devices covered by different textile fabrics, produce a large variety of ornamental fancy flowers for trimmings, fancy bouquets, and decorative purposes.

Having thus described my invention, I claim as new and desire to secure by Letters Patent—

An imitation flower consisting of a stem and core, a strip of fur wrapped spirally around said stem and core, and a fastening-wire wound spirally around the stem and strip, substantially as set forth.

In testimony that I claim the foregoing as my invention I have signed my name in presence of two subscribing witnesses.

EUGEN FRIEDLAENDER.
